UNITED STATES PATENT OFFICE.

STEVEN C. COPOLL, OF LOS ANGELES, CALIFORNIA.

MEASURING ATTACHMENT FOR SEWING MACHINES.

1,427,676.

Specification of Letters Patent. Patented Aug. 29, 1922.

Application filed June 27, 1921. Serial No. 480,877.

To all whom it may concern:

Be it known that I, STEVEN C. COPOLL, a citizen of the United States, residing at Los Angeles, in the county of Los Angeles and 5 State of California, have invented new and useful Improvements in Measuring Attachments for Sewing Machines, of which the following is a specification.

This invention relates generally to sewing 10 machines, and more particularly to a device that is adapted to be attached to hemstitch machines, and which will be effective in accurately measuring the lineal amount of hemstitching done by the machine.

15 The principal objects of my invention are to provide a relatively simple and practical and compact measuring device that is capable of being readily applied to hemstitch machines, to provide a measuring device that 20 requires but very little power in its operation, to provide a device of the character described that comprises a relatively small number of operating parts thereby minimizing the liability of its becoming inoperative due to disarrangement of its parts, 25 and further to provide a device that is very effective in performing its intended functions.

With the foregoing and other objects in 30 view, my invention consists in certain novel features of construction and arrangement of parts that will be hereinafter more fully described and claimed and illustrated in the accompanying drawings, in which:

35 Figure 1 is a side elevational view of a measuring attachment of my improved construction, the same being shown in operative position on the side of a hemstitch machine.

Fig. 2 is an enlarged horizontal section 40 taken on the line 2—2 of Fig. 1.

Fig. 3 is a plan view of my improved measuring attachment in position upon a hemstitch machine and with parts of said attachment in horizontal section.

45 In the drawings I have illustrated my improved attachment in position upon any standard hemstitch machine such as that shown in Patent No. 893,372, issued June 30, 1908, said machine including the usual 50 head or frame 10, needle vibrating levers 11, rocker arm 12 that is utilized for imparting vibratory movement to the needle vibrating levers, said rocker arm being pivotally mounted at 13 to the head or frame 10, and 55 the rocker arm actuating cam 14 which latter is contained within a suitable housing 15

that is arranged on the side of the head or frame 10.

My improved measuring device includes a plate 16 that is secured by a screw, such 60 as 17, on the side of the head of frame 10 immediately adjacent to and over the cam housing 15, and mounted on the right hand of said plate is an ordinary counting device 18 preferably of the type employing a plurality of discs bearing numerals on their edges, and a horizontally disposed row of said numerals being visible through an opening in the housing of the counter. This counting device, which is of a well known 70 type, is provided with an operating arm or lever 19, the free end of which projects a short distance from the end of the housing of the counter.

Mounted for rotation on a stud or pin 20 75 that is seated in plate 16 is a ratchet wheel 21. The number of teeth thereon corresponding with the number of hemstitch openings that are produced in each inch of goods passed through the machine. For 80 instance, if the machine produces eight hemstitch openings on each lineal inch of goods, then ratchet wheel 21 is provided with eight teeth, as shown in Fig. 1.

Pivottally mounted on the lower end of 85 rocker arm 12 is one end of a spring pressed arm 22, the free end of which is formed into a hook 23 that is adapted to engage the teeth of ratchet wheel 21. Seated in plate 16 between the counting device 18 and 90 the pin or stud 20 is a pin or stud 24, and journaled thereon is a disc 25 having formed in its periphery thirty-six teeth. Projecting outwardly from the face of ratchet wheel 21 is a pin 26 that is adapted to engage between the teeth on the edge of disc 25, and 95 projecting laterally from the face of disc 25 and beneath the teeth on the edge thereof is a pin or finger 27 that is adapted to engage the free end of the lever 19 of the counting device 18.

The parts just described are arranged so that with each complete rotation of ratchet wheel 21 the pin 26 projecting from the outer face thereof will engage between the teeth of disc 25 and move the same one thirty-sixth of a complete revolution, and with each complete revolution of said disc 25, pin 27 will engage and actuate lever 19 so that the unit disc of counting device 18 110 is moved one space or one-tenth of a complete revolution.

In the operation of the hemstitching machine, needle vibrating cam 14 actuates rocker arm 12 so as to rock or vibrate the same upon its axis 13 and consequently imparting vibratory movement to the needle vibrating levers 11, and during such operations the point of hook 23 moves backwardly and forwardly upon the face of one of the teeth of ratchet wheel 21 without imparting movement thereto.

At the completion of one of the small hemstitched openings in the goods, the latter is shifted the distance of one opening, at which time the cam 14 moves the lower end of rocker arm laterally a sufficient distance to cause hook 23 to rotate ratchet wheel 21 one-eighth of a complete revolution. These operations are successively repeated with each opening in the goods that are hemstitched until ratchet wheel 21 has made a complete revolution, whereupon pin 26 will engage between the teeth of disc 25 to move the same one thirty-sixth of a complete revolution, thus measuring eight hemstitched openings or one inch of work. As disc 25 makes one complete revolution, finger 26 engages the free end of lever 19 and consequently imparting movement to the unit disc of the counter and thereby moving the same to indicate one yard of work done.

Ratchet wheel 21 is readily removable from the plate 16 in order that it may be readily detached and replaced by a wheel having a different number of teeth, it being understood that the number of teeth of the ratchet wheel that is applied for use corresponds with the number of hemstitched openings in each inch of work done by the machine, and in order to prevent said ratchet wheel from rotating too freely, a friction disc, such as 20^a, is positioned between the head of pin or stud 20 and the outer surface of said ratchet wheel.

A measuring attachment of my improved construction is comparatively simple, is very positive and accurate in operation, requires very little power in its operation, may be readily attached to a hemstitch machine and is effective in accurately measuring and indicating all work done by the machine.

It will be readily understood that minor changes in size, form and construction of the various parts of my improved attachment for hemstitch machines may be made and substituted for those herein shown and described without departing from the spirit of my invention, the scope of which is set forth in the appended claims.

I claim as my invention:

60 1. A measuring attachment for hemstitch machines comprising a counting device hav-

ing an operating arm, a toothed disc arranged for operation adjacent to said counting device, a finger projecting from said toothed disc for engaging the arm of the counting device, a ratchet wheel mounted for operation adjacent to the toothed disc and adapted to be intermittently rotated by operating parts of the sewing machine to which the device is applied, and means on said ratchet wheel for imparting step by step rotary motion to said toothed disc.

2. A measuring attachment for hemstitch machines comprising a counting device having an operating arm, a toothed disc arranged for operation adjacent to said counting device, a finger projecting from said toothed disc for engaging the arm of the counting device, a ratchet wheel mounted for operation adjacent to the toothed disc and adapted to be intermittently rotated by operating parts of the sewing machine to which the device is applied, means on said ratchet wheel for imparting step by step rotary motion to said toothed disc, and friction means for controlling the rotation of said ratchet wheel.

3. In a hemstitching machine including a rocker arm, a cam for vibrating the rocker arm and laterally shifting one end of the latter at intervals, counting mechanism, and means operable by the lateral movement of the rocker arm for actuating the counting mechanism.

4. In a hemstitching machine, including a rocker arm, a cam for vibrating the rocker arm and laterally shifting one end of the latter at intervals, counting mechanism, and means operable by the lateral movement of the rocker arm for actuating the counting mechanism, said means including a ratchet wheel, and a pawl carried by the rocker arm and associated with the ratchet wheel in such manner that it is actuated to rotate the ratchet wheel only when the rocker arm is shifted laterally.

5. A measuring attachment for hemstitching machines comprising a counting mechanism, and means for actuating the counting mechanism which is adapted for operation by and only when the rocker arm of a machine is laterally shifted.

6. A measuring attachment for hemstitching machines comprising a counting mechanism, and means for actuating the counting mechanism comprising a ratchet and a pawl associated with the ratchet so as to advance the latter only at the end of a hemstitch.

In testimony whereof I have signed my name to this specification,

STEVEN C. COPOLL.
